DESIGN FOR A DISPLAY STAND FOR MATERIAL FOR WALL COVERINGS, FLOORINGS, RUGS, OR THE LIKE

Charles Eugene Stephenson, New York, N. Y.

Application January 31, 1940, Serial No. 89,899

Term of patent 14 years

To all whom it may concern:

Be it known that I, Charles Eugene Stephenson, a citizen of the United States, residing in New York, in the county of New York and State of New York, have invented a new, original, and ornamental Design for a Display Stand for Material for Wall Coverings, Floorings, Rugs, or the Like, of which the following is a specification, reference being had to the accompanying drawing, forming a part thereof, in which:

Fig. 1 is a front perspective view of the display stand, for material for wall coverings, floorings, rugs or the like, showing my new design;

Fig. 2 is a top plan view thereof, on an enlarged scale;

Fig. 3 is an end elevational view, on the same scale as shown in Fig. 2; and

Fig. 4 is a front elevational view, also on the same scale as Fig. 2.

The rear and end not shown are plain.

I claim:

The ornamental design for a display stand for material for wall coverings, floorings, rugs, or the like, substantially as shown and described.

CHARLES EUGENE STEPHENSON.
